UNITED STATES PATENT OFFICE.

WILLIAM H. MANEY, OF FRANKLIN, TENNESSEE, ASSIGNOR OF ONE-HALF
TO NATHAN E. MORRIS, JR., OF FRANKLIN, TENNESSEE.

WASHBOARD.

SPECIFICATION forming part of Letters Patent No. 695,410, dated March 11, 1902.

Application filed December 21, 1901. Serial No. 86,747. (No model.)

To all whom it may concern:

Be it known that I, WILLIAM HARDY MANEY, of Franklin, in the county of Williamson and State of Tennessee, have invented a new and useful Improvement in Washboards, of which the following is a specification.

The object of my invention is to provide a washboard which shall not only cause a better disposition of the water, suds, and clothes upon the same during the act of washing, but which shall also lessen the arduous labor of hand-washing; and it consists in a washboard which is concave on its washing-face and convex on its back, the axis about which these curves are described being longitudinal to the board and the side pieces so arranged that their rear edges are in advance of the middle convex back portion, as hereinafter fully described with reference to the drawings, in which—

Figure 1 is a perspective view of the washboard. Fig. 2 is a cross-section on line 2 2 of Fig. 1; Fig. 3, a cross-section on line 3 3 of Fig. 1. Fig. 4 is a plan view of a tub with the washboard arranged therein; and Fig. 5 is a vertical section of the same, taken longitudinally through the washboard on line 5 5 of Fig. 4.

In the drawings, A A represent the two side pieces. B is the front, and B' the back. The front is preferably made of corrugated metal, as usual, and the back of wood; but both are curved in cross-section, so as to present a concave front face and a convex back. The curvature is transverse to the longitudinal axis of the board—*i. e.*, it is described about a longitudinal axis as a part of the periphery of a cylinder. The radius of the curve is preferably such as to correspond to the curve of the ordinary washtub, so that when placed in the tub the washboard will lie close against the wall of the tub next to the operator. The object of this is twofold. First, it causes the line of rubbing on the washboard to lie very much closer to the operator and lessens the reach which is so trying on the back, thus greatly reducing the arduous labor of hand-washing. That this may be more clearly understood it will be seen that if a washboard be straight in transverse direction across its

back it will when in the tub occupy the position of the chord of an arc in the tub, as shown by line z z, Fig. 4; but when curved, as in my invention, the washboard lies close against the sides of the tub, and in my invention the line of rubbing is shown at y y of Fig. 5, whereas it would be at x x with the straight backboard. It is obvious that as the line y y is closer to the operator than x x the position y y entails upon the operator very much less reach and consequent fatigue upon the person's back. Furthermore, with my invention a longitudinal central trough is formed, which causes the water and suds to flood the clothes better when lifted on the board and also causes the water to drain away from the sides.

At the top of the washboard there is the recess C, which forms the soap-receptacle. Such receptacles are common in washboards; but in my invention it is not only made of the same curved cross-section as the lower part of the board, but it projects beyond the lower portion to form a shoulder s, that hooks over the top edges of the tub, which causes it to be firmly held thereon, even if the terminal legs or ends of the side pieces A do not reach the opposite side of the tub.

In pointing out more clearly the distinguishing features of my invention I would state that the results described in my specification are rendered possible by the fact that the rear edges of the side pieces A A or the edges next to the operator are in advance of the middle of the convex back B'. In other words, a straight line drawn across from the rear edge of one side piece A to the other would not fall behind the curved back B', but would intersect the curve of the same after the manner of the chord of an arc. This, it will be seen, is necessary in order to allow the washboard to sit closer to the operator, as described.

Having thus described my invention, what I claim as new, and desire to secure by Letters Patent, is—

1. A washboard having both its front and back curved about a longitudinal axis, the front being concaved, and the back convex and having side pieces whose rear edges are

in advance of the middle part of the convex back, substantially as and for the purpose described.

2. A washboard having both its front and back curved about a longitudinal axis, the front being concave, and the back convex, and having side pieces whose rear edges are in advance of the middle part of the convex back, and also a curved soap-receptacle at

its upper end projecting on the back beyond the lower portion to form a shoulder adapted to catch against the sides of a tub substantially as and for the purpose described.

WILLIAM H. MANEY.
